FOLDED SLOT ANTENNAE

Rex Henry John Cary, Great Malvern, England, assignor to National Research Development Corporation, London, England, a British corporation

Application June 9, 1952, Serial No. 292,529

Claims priority, application Great Britain June 20, 1951

38 Claims. (Cl. 343—767)

This invention relates to folded-slot antennas and has particular reference to methods of reactance compensation of such antennas in order to obtain a wide frequency band.

Antennas of the folded-slot type are well-known and have been described and used by H. G. Booker and others, particularly in connection with antennas for radar. The characteristics and advantages of such antennas, too, are well-known. One of these advantages is that of obtaining, by reactance compensation, a wideband antenna for a given standing wave ratio. Various ways of obtaining such wide-band antennas by reactance compensation have been described previously but these appear to give a maximum bandwidth of $\pm 20\%$ at the standing wave ratios acceptable for use in television and frequency modulation systems. For purposes where a larger standing wave ratio can be tolerated it is evident that some improvement in bandwidth will result from the actual relaxation of the standing wave ratio itself. This further improvement however is small in most cases and where bandwidths, for example, of the order of an octave at the larger standing wave ratio are required other methods must be adopted.

Additionally, in an aircraft, there is often required a suppressed antenna which can conveniently be provided by means of a slot in the aircraft skin backed by a cavity formed from part of the aircraft inside structure. Since the use of a cavity behind a slot effectively doubles its impedance the use of a folded slot has advantages in that folding a slot quarters this impedance. Moreover there is often insufficient room in the cavity behind the slot for a suitable probe with which to feed the slot and again the folded slot is advantageous since it can be directly connected to the feeder and then presents a reasonably suitable impedance to the feeder of the type (e. g. coaxial) generally used.

Now, in most aircraft antenna installations a wideband is desired and, in a great many cases such as in some navigational aids, a larger standing wave ratio can be accepted than is normally required for television and frequency modulation systems. There is thus a requirement here for an improved wide band folded slot antenna, especially for use in cases of the larger standing wave ratio.

It is an object of the invention to provide a folded-slot antenna with an improved bandwidth particularly when used with the larger standing wave ratios.

It is a further object of the invention to provide such a folded slot antenna which, if desired, may be connected to, and will match a low-impedance feeder such as the coaxial feeder.

A subsidiary object of the invention is the provision of a folded slot antenna suitable for installation as a suppressed antenna in the skin of an aircraft and having an impedance suitable for matching with and connecting to a coaxial type of feeder.

According to the invention there is provided a reactance-compensated folded slot antenna in which the inherent

2

reactance of the folded slot antenna is compensated within desired limits over a frequency band by suitable slot-feeder reactance in series therewith, characterised in that said series reactance is made up of two parts, each part having a different reactance-frequency characteristic such that the desired compensation is effected within the desired frequency band.

It is possible by suitable dimensioning and arrangement of the series slot feeder reactances of the folded-slot to obtain a resultant compensated reactance-frequency characteristic which is a continuous curve oscillating about the zero reactance ordinate and cutting it at least five times, the standing wave ratio remaining within predetermined limits over a wide frequency band.

According to a particular feature of the invention there is provided a reactance-compensated folded-slot antenna asymmetrically fed. Such asymmetrical feeding is obtained when, by physical offsetting of the feed point or electrical offsetting of the feed point of the folded slot, the slot feeder reactances are not symmetrical about the feed point.

After choosing a suitable feed point to give a desired slot impedance the frequency-band covered by the folded slot antenna may be determined by altering reactances of the slot feeders (e. g. by altering the lengths of the centre or fold conductor in the two parts of the slot) in order to obtain reactance compensation.

For example, in the case of the simplest folded slot comprising a half-wavelength rectangular slot in a conducting sheet with a single strip or conductor running longitudinally along the middle of the slot, asymmetrical feeding consists of feeding between one side of the slot and the conductor by a feeder at a point less than quarter wavelength from one end of the slot. It will be appreciated that with such feeding the slot will comprise two parts in parallel. One part consists of the slot feeder reactance looking in at the feed point towards one end of the slot, in series with the slot impedance as seen in that direction, and, the other the slot-feeder reactance looking in at the feed point towards the other end of the slot in series with the slot impedance as seen in that direction. The differing frequency-reactance characteristics of the two slot-feeders enable reactance compensation to be obtained over a wide waveband and, in particular, prevent simultaneous failure of feeding should both the slot-feeder reactances approach infinity together as they will do when the extremes of a wide frequency band are considered for a symmetrically fed antenna. The two different slot-feeder reactances do not approach infinity simultaneously and, since the parts of the folded slot in which they exist are in parallel, the feed impedance of the slot can be arranged never to approach infinity within the wide frequency band. Reactance compensation is thus possible over a wider range of frequency than hitherto.

In order to show the principles on which the invention is based and two methods by which it may be performed several embodiments will now be described as examples with reference to the accompanying drawings in which:

Fig. 1 shows generally a folded slot,

Fig. 2 shows a general equivalent circuit of a folded slot,

Figs. 3 to 10 show typical arrangements of a reactance compensated folded slot according to the invention,

Figs. 11 and 12 show the folded slot arrangement of Fig. 10 as used in a high speed aircraft, and

Fig. 13 shows a further folded slot arrangement having an allround radiation pattern.

In the diagram of Figs. 1, 3 to 10 and 13 cross-hatching, going upwards from left to right, is conveniently used to

indicate a conducting surface in which the various slots are cut.

Reactance-compensation of a folded-slot antenna has been described by Monteath (Proc. I. E. E., vol. 97, part III, No. 50, Nov. 1950) with particular reference to that type of folded-slot in which one slot-feeder only has been retained of the two symmetrical slot-feeders of the Booker-Bailey folded slot. In the following examples reactance-compensation is achieved by making the slot-feeders asymmetrical and the two parts which they comprise serve as series reactances with which to compensate individually the corresponding parts of the inherent reactance of the folded slot antenna with one of which each part (slot-feeder) is in series. The principles on which such reactance compensation is based will now be further discussed with reference to Figs. 1 and 2 of the drawings. In Fig. 1 a folded slot 1 is shown fed at two points A, B. The folded slot 1 comprises a slot WXYZ cut in a sheet of conducting material and "folded" by the insertion of a centre conductor ACDEF. The feed to the points AB 20 may comprise any suitable twin feeder and can be anywhere between the edge DE or CF of the centre conductor ACDEF and the edge WX, or ZY respectively of the slot WXYZ.

A folded slot fed in this manner can be represented to a first approximation by an equivalent circuit as shown in Fig. 2. Looking in at the feed points A, B towards the left hand end of the slot, the slot feeder reactance is shown as X_2 , the radiation resistance as R_1 , and the inherent reactance as X_1 . X_1 and R_1 and X_2 the slot feeder, represent the part of the slot to the left of the feed points A, B. Similarly looking in at the feed points AB towards the right hand end of the slot the slot feeder reactance is shown as X_3 , the radiation resistance as R_2 , and the inherent reactance as X_4 .

Where a cavity is placed behind the slot WXYZ the cavity may be taken as introducing additional reactances X_5 and X_6 . The connections to these reactances are shown dotted because, as will be apparent as the description proceeds, the effect of the cavity may be neglected from the point of view of the invention and taken into account quite simply at a later convenient stage.

Now, taking the completely symmetrical case where the centre conductor CDEF is symmetrical disposed in the slot WXYZ and the feed points A and B are in the middle of edges CF and ZY respectively, it will be easily appreciated that $X_2=X_3$; $R_2=R_1$ and $X_4=X_1$. Thus whenever X_2 reaches infinity there will be no feed of energy to the slot WXYZ because the feeder reactance X_3 will also reach infinity. Therefore, the band of frequencies over which the folded slot will act will be limited accordingly as X_2 and X_3 simultaneously approach infinity. Reactance compensation is only possible on a very limited basis since compensation by making X_3 the conjugate of X_4 will also mean the same thing as regards X_2 and X_1 and failure will be simultaneous owing to the equality of X_2 and X_3 .

If, however, either the feed points A, B, or the centre conductor CDEF, or both, are arranged asymmetrically so that the reactances X_2 and X_3 reach infinity at entirely different frequencies, feed of energy will take place through either one slot feeder or the other (i. e. to the left or right of feed points A, B) or at some frequencies, through both. In any event the feed to the slot 1 will not fail over a wide band of frequencies. This asymmetry will mean that X_1 is also different from X_4 and therefore compensation either between X_3 and X_4 , or between X_2 and X_1 can be arranged, over a very wide band of frequencies without the feed to the slot 1 failing.

Referring again to the effect of adding a cavity behind the slot WXYZ, it will be seen that if the dotted connections of Fig. 2 are assumed to be made, then, suitable adjustments to slot feeder reactances X_3 and X_2 will compensate X_6 and X_5 respectively in parallel with X_4 and X_1 , again respectively.

In the following examples it will be assumed for the

sake of simplicity that wherever a cavity is desired behind a folded slot the necessary corrections in the reactance compensation will be made in accordance with the above and so no reference has been made to the use of cavities in the examples.

Reactance-compensation may thus be achieved over a wide frequency band particularly where a variation of standing wave ratio greater than that acceptable for television and frequency transmissions modulation can be tolerated.

Example 1

Fig. 3 shows a half-wavelength folded slot comprising a slot 1, cut in a conducting sheet 2, in which a flat strip 3 is symmetrically disposed in known arrangement. Adjacent feed points A and B are provided in the strip 3 and the perimeter of slot 1 respectively. The points A, B are at a distance l from centre line C_L. It will be apparent that there are two asymmetrical slot-feeders: One, looking in at the points AB towards the left of the figure, of physical and electrical length l_1 , and one, looking in at the points AB towards the right of the figure, of physical and electrical length l_2 . The slot-feeder reactances seen will be different and will obviously vary differently in relation to frequency; in particular each slot-feeder reactance will approach infinity at differing frequencies.

In the arrangement of Fig. 1 it will be seen that the feed points A, B may be chosen to provide a suitable impedance for use with different types of antenna feeder but that the position of complete symmetry where $l=0$ and the effective electric lengths of l_1 and l_2 are equal must not be used. Since, however, the shorter, physically, the slot feeder l_1 becomes, the poorer the feed of energy possible into the slot 1, from the shorter feeder l_1 , there is a limit to the reduction in length of slot feeder l_1 , possible or desirable.

Example 2

In effecting the required reactance compensation it is possible to change the effective electrical length of the slot feeder l_1 of the arrangement of Example 1 by inserting dielectric filling in the slot 1 to the left of the line drawn through the feed points A, B. If the dielectric filling has a dielectric constant of n then the electrical length of the slot feeder will be $l_1\sqrt{n}$. The effective electrical length of either slot feeder may be changed in this way, of course.

Example 3

Referring now to Fig. 4 it will be seen that reactance compensation is here being effected by a method in addition to those described with reference to Example 1 above, by the adjustment of the dimensions of the centre conductor. In the Fig. 4 the centre conductor to the left of the feed points A, B may be made as thin as mechanically desirable to obtain a required compensation. The slot to the left of the line through the feed points A, B is filled with dielectric of dielectric constant n to give an electrical slot feeder length to the left of the feed points A, B, of $l_1\sqrt{n}$. The width l_3 of the centre conductor to the right of the feed points A, B is determined according to the compensating slot feeder reactance required.

Example 4

Alternatively, the transverse dimensions of the slot itself may be adjusted to achieve the required slot feeder reactance when reactance compensation is being performed. In Fig. 5 the transverse slot with l_4 to the left of the feed points A, B is made narrow to give the necessary value of compensating slot feeder reactance.

Example 5

Another method of adjusting the electrical lengths of the slot feeders is by adding lumped or distributed reactance as indicated in Fig. 6, or in Fig. 6A, where a lumped series reactance $\boxtimes$ is added in series with the slot feeder to the left of the feed points A, B. Conveniently, the series reactance $\boxtimes$ may comprise a suitable

coil connected across a gap in the part of the centre conductor forming slot feeder length l_1 of Fig. 6 or in the case of the connection shown dotted in Fig. 3 a condenser would be convenient.

Example 6

In an alternative arrangement of the type shown in Example 5 the slot feeder length l_1 may be extended to join to the left-hand end of the slot 1 as shown in Fig. 7. The necessary series reactance $\square$ is added as before in series with the slot feeder length l_1 .

Example 7

Alternatively the slot feeder length l_2 may be extended to join to the right hand end of the slot 1 as shown in Fig. 8.

Example 8

In some cases it may be desirable to extend one of the slot feeders to a point beyond the end of the slot 1 to obtain a desired value for a slot feeder reactance. This may be achieved as shown in Fig. 9 where the slot feeder length l_2 has been extended beyond the right hand end of the slot 1 and there connected to the surface 2 in which the slot 1 is cut.

Example 9

Yet another alternative arrangement is shown in Fig. 10 in which the slot feeder l_1 has been made as a strip and the slot feeder l_2 has been made as thin as mechanically allowable.

The actual electrical-mechanical interpretation as applied to a suppressed antenna for a high speed aircraft is shown in Figs. 11 and 12. The slot 1 is cut in the conducting surface 2 of the aircraft skin and covered on the inside with a sheet of dielectric material 4 which is fastened to the aircraft surface 2 by rivets 4a. The centre conductor 3 is made up of a conducting strip 3A of length l_1 and welded to a thin conducting rod 3B of length l_2 thus forming the two slot feeders 3A and 3B of Fig. 10. The centre conductor 3 is fastened in the slot 1 by clamping it onto the dielectric sheet 4 by clamps 4b. A coaxial feeder 6 is fastened and connected electrically by its sheath 6a to the aircraft surface 2 at the feed point B and by its inner conductor 6b to the feed point A at the junction of the slot feeders 3A, 3B.

The arrangement of Figs. 10, 11 and 12 whilst giving two sectional fillings of dielectric of effectively different dielectric constant, i. e. plate of dielectric for the section 3A and plate of dielectric plus air for the section 3B, has the advantages of simplicity and strength. It is customary in the case of slots used in aircraft to enclose the aircraft side of the slot by means of a resonant chamber. This is generally arranged to be a part of the internal bracing or structure of the aircraft.

Example 10

The invention is not limited to straight slots but may be used where it is necessary or preferable to have the slot 1 in other configurations. An example of this use is for an aircraft antenna in which an all-round radiation pattern is required. In such a case a folded slot 1 may be provided in the configuration shown in Fig. 13. The conducting surface 2 of the aircraft is shown by the cross-hatching and the walls 5 of a resonant chamber which enclose the back of the aerial are shown in plan. In the structural design of the aircraft such walls 5 are conveniently made to form a useful part of the internal aircraft structure, which also provides the enclosing means, parallel to the aircraft surface 2, for the resonant chamber.

The slot 1 is filled with a sheet of dielectric of suitable dielectric constant and on this sheet the strip 3 of the folded slot 1 is fastened. Terminals A, B are provided at the feed points and connect to a coaxial feeder. The strip 3 is displaced in the slot 1, in known manner, as shown, to provide a lower impedance for the slot 1 to match the particular feeder used without the necessity of

moving the feed points A, B still further from the symmetrical position and so reducing the energy feed to the slot 1. Coupling may exist between the parts of the slot which extend in opposite ways from A, B feedpoints but this will merely modify the values of the inherent slot impedances (R_1+X_1) and (R_2+X_4) of Fig. 2 and will not affect the principle or successful performance of the invention.

It will be easily seen from the foregoing that a large number of variations of an asymmetrically fed folded slot antenna are possible without going outside the scope of the invention and that the variations illustrated and described are by way of example only; the invention is not limited to such variations in carrying it into effect. Also the displacement of the strip 3 in the slot 1 and the configuration of slot 1 adopted in the example of Fig. 13 for the purposes stated are capable of application to any of the examples shown for similar purposes.

Further, it will be quite obvious to those to whom this specification is addressed, how enclosing of one side of the slot by a resonant chamber will modify the reactance characteristics of the folded slot and what changes of compensating reactance are necessary to compensate for this; such modification will however in no way prevent the successful application of the invention in any particular case.

I claim:

1. In a reactance compensated folded slot antenna in which the inherent reactance of the folded slot is compensated within desired limits over a frequency band by

means of slot feeder reactance in series therewith, the combination of a conductive sheet having a slot therein, a centre conductor located in the slot, feeder connection means comprising a pair of feed elements connected one to a feed point on said centre conductor and the other to the edge of said slot adjacent the feed point on said centre conductor, the construction being such that the two slot feeders which result are connected in parallel to said feeder connection means and are of electrically dissimilar dimensions whereby within the operative frequency band at least one of said slot feeders provides effective feed of energy to the slot from the feeder connection.

2. In a reactance compensated folded slot antenna in which the inherent reactance of the folded slot is compensated within desired limits over a frequency band by

means of slot feeder reactance in series therewith, the combination of a conductive sheet having a slot therein, a centre conductor located in the slot, feeder connection means for connecting a source of radio frequency energy

across the centre conductor and the adjacent edge of the slot, the slot and the centre conductor thereby defining two slot-feeders in parallel connected to the feeder connection means, the construction being such that the two slot feeders which result are constructed with dissimilar electrical characteristics, the two slot-feeders thereby reaching at separate frequencies within the frequency band the high value of reactance which prevents the effective feed of energy to the slot from the feeder connection means via the slot-feeder.

3. A reactance compensated folded slot antenna in which the inherent reactance of the folded slot is compensated within desired limits over a frequency band by

means of slot feeder reactance in series therewith, the folded slot including a conductive sheet having a slot therein, a centre conductor located in the slot, feeder connection means for connecting a feeder across the centre conductor and the adjacent edge of the slot, the slot and the centre conductor thereby defining two slot feeders for feeding in parallel from the feeder connection means, and dielectric filling means for filling at least part of the aperture between the slot and the centre conductor, the dielectric filling means being so chosen and located, the feeder connection means being so located, and the centre conductor and slot configurations being so arranged that the two slot feeders extending each side of the feeder

connection means are constructed to follow different frequency characteristics for the slot feeder reactances to reach at separate frequencies within the frequency band the high value of reactance which prevents the effective feed of energy to the slot from the feeder connection means via the slot feeder.

4. A reactance compensated folded slot antenna as claimed in claim 3 wherein the feeder connection means is located nearer one end portion of the slot than the other.

5. A reactance compensated folded slot antenna as claimed in claim 4, wherein one end portion of the centre conductor is continued and connects to an adjacent end portion of the slot.

6. A reactance compensated folded slot antenna as claimed in claim 4, wherein one end portion of the centre conductor is continued beyond and over the adjacent end portion of the slot and connects at its extremity to the conductive sheet.

7. A reactance compensated folded slot antenna as claimed in claim 4, wherein the centre conductor comprises two parts, one extending along the slot in one direction from the feeder connection means and one extending along the slot in the opposite direction one part being smaller transversely than the other and the dielectric filling means being located in the aperture of the slot containing the one part of the centre conductor.

8. A reactance compensated folded slot antenna as claimed in claim 4, wherein the centre conductor comprises two parts, one extending along the slot in one direction from the feeder connection means and one extending along the slot in the opposite direction one part being smaller transversely than the other and the slot likewise comprises two parts, one extending in one direction from the feeder connection means and one extending in the opposite direction the part of the slot containing the smaller part of the centre conductor being smaller transversely than the part of the slot containing the other part of the centre conductor.

9. A reactance compensated folded slot antenna as claimed in claim 3 comprising a lumped reactance element connected in series with the centre conductor, the value of reactance and location being so arranged as to contribute to the electrical characteristics of at least one of the slot feeders.

10. A reactance compensated folded slot antenna as claimed in claim 9 wherein the feeder connection means is located nearer one end portion of the slot than the other.

11. A reactance compensated folded slot antenna as claimed in claim 9, wherein the lumped reactance element is connected intermediately of the centre conductor in that part associated with one slot feeder.

12. A reactance compensated folded slot antenna as claimed in claim 9, wherein the lumped reactance element is connected between one end portion of the centre conductor and one adjacent end portion of the slot.

13. A reactance compensated folded slot antenna as claimed in claim 12, wherein the lumped reactance element comprises a condenser.

14. A reactance compensated folded slot antenna in which the inherent reactance of the folded slot is compensated within desired limits over a frequency band by means of slot feeder reactance in series therewith, the folded slot including a conductive sheet having a slot therein, a centre conductor located in the slot, feeder connection means for connecting a feeder across the centre conductor and the adjacent edge of the slot, the slot and the centre conductor thereby defining two slot-feeders for feeding in parallel from the feeder connection means, and a lumped reactance element connected in series with the centre conductor, the value of reactance and the location thereof relative to the centre conductor, the feeder connection location, and the centre conductor and slot configurations being so arranged that the two slot

feeders extending each side of the feeder connection means are constructed to follow different frequency characteristics for the slot feeder reactances to reach at separate frequencies within the frequency band the high value of reactance which prevents the effective feed of energy to the slot from the feeder connection means via the slot feeder.

15. A reactance compensated folded slot antenna as claimed in claim 14 wherein the feeder connection means is located nearer one end portion of the slot than the other.

16. A reactance compensated folded slot antenna as claimed in claim 14, wherein the lumped reactance element is connected intermediately of the centre conductor in that part associated with one slot feeder.

17. A reactance compensated folded slot antenna as claimed in claim 14, wherein the lumped reactance element is connected between one end portion of the centre conductor and one adjacent end portion of the slot.

18. A reactance compensated folded slot antenna as claimed in claim 14, wherein the lumped reactance element comprises a condenser.

19. A reactance compensated folded slot antenna in which the inherent reactance of the folded slot is compensated within desired limits over a frequency band by means of slot feeder reactance in series therewith, the folded slot including a conductive sheet having a slot therein, a centre conductor located in the slot, feeder connection means for connecting a feeder across the centre

25 conductor and the adjacent edge of the slot, the slot and the centre conductor thereby defining two slot-feeders for feeding in parallel from the feeder connection means, the feeder connection means being so located and the centre conductor and slot configurations being so arranged that

30 the two slot feeders extending from each side of the feeder connection means are constructed to be electrically dissimilar and therefore follow different frequency characteristics for the slot feeder reactances to reach at separate frequencies within the frequency band the high value

35 of reactance which prevents the effective feed of energy to the slot from the feeder connection means via the slot feeder.

20. A reactance compensated folded slot antenna as claimed in claim 19 wherein the feeder connection means is located nearer one end portion of the slot than the other.

21. A reactance compensated folded slot antenna as claimed in claim 20 wherein one end portion of the centre conductor is continued and connects to an adjacent end portion of the slot.

22. A reactance compensated folded slot antenna as claimed in claim 20, wherein one end portion of the centre conductor is continued beyond and over the adjacent end portion of the slot and connects at its extremity to the conductive sheet.

23. A reactance compensated folded slot antenna as claimed in claim 20, wherein the centre conductor comprises two parts, one extending along the slot in one direction from the feeder connection means and one extending along the slot in the opposite direction one part being smaller transversely than the other.

24. A reactance compensated folded slot antenna as claimed in claim 20, wherein an open box of conductive material is positioned against the conductive sheet so as to enclose within its open edges that part of the sheet in which the slot is located, so forming a resonant cavity for the antenna.

25. A suppressed antenna for use in aircraft and the like having conductive external skins comprising a reactance compensated folded slot antenna in which the inherent reactance of the folded slot is compensated within desired limits over a frequency band by suitable slot feeder reactance in series therewith, the folded slot including a conductive sheet part of the aircraft skin having a slot therein, a centre conductor located in the slot, feeder connection means for connecting a feeder across

the centre conductor and the adjacent edge of the slot and located nearer one end portion of the slot than the other, the slot and the centre conductor thereby defining two slot feeders for feeding in parallel from the feeder connection means, and a dielectric sheet closing the aperture of the slot, the centre conductor being located in the slot by being mounted on the sheet and comprising two parts to one part each side of the feeder connection means, one part being mounted in contact along its length with the dielectric sheet the other part having support members and being supported thereby out of contact with the dielectric sheet, whereby two electrically asymmetric slot feeders are defined extending each side of the feeder connection means and follow different frequency characteristics for the slot feeder reactances to reach at separate frequencies within the frequency band the high value of reactance which prevents the effective feed of energy to the slot from the feeder connection means via the slot feeder.

26. A suppressed antenna for use on aircraft and the like as claimed in claim 25, wherein an open box of conductive material is positioned against the conductive aircraft skin so as to enclose within its open edges that part of the sheet in which the slot is located, so forming a resonant cavity for the antenna, said open box comprising parts of the aircraft structure behind the aircraft skin.

27. A suppressed antenna for use on aircraft and the like having conductive external skins comprising a reactance compensated folded slot antenna in which the inherent reactance of the folded slot is compensated within desired limits over a frequency band by suitable slot feeder reactance in series therewith, the folded slot including a conductive sheet part of the aircraft skin having a slot therein, a portion of the aircraft structure behind the skin comprising a box-like resonant cavity for the slot and having a fore-shortened partition member which forms two communicating compartments in the cavity, the slot being so located and shaped to be enclosed by both compartments, a centre conductor located in the slot, feeder connection means for connecting a feeder across the centre conductor and the adjacent edge of the slot and located nearer one end portion of the slot than the other, the slot and the centre conductor thereby defining two slot feeders for feeding in parallel from the feeder connection means, and a dielectric sheet closing the aperture of the slot, the centre conductor being located in the slot by being mounted on the sheet, whereby two electrically asymmetric slot feeders are defined extending each side of the feeder connection means and follow different frequency characteristics for the slot feeder reactances to reach at separate frequencies within the frequency band the high value of reactance which prevents the effective feed of energy to the slot from the feeder connection means via the slot feeder.

28. In a reactance compensated folded slot antenna in which the inherent reactance of the folded slot is compensated within desired limits over a frequency band by means of a slot feeder reactance in series therewith, the combination of a conductive sheet having a slot therein, a centre conductor located in the slot, feeder connection means comprising a pair of feed elements connected one to a feed point on said centre conductor and the other to the edge of said slot adjacent the feed point on said centre conductor, said feed points being located nearer one end portion of the slot than the other, thereby defining two electrically asymmetric slot feeders connected in parallel to said feeder connection means, whereby within the operative frequency band at least one of said slot feeders provides effective feed of energy to the slot from the feeder connection.

29. In a reactance compensated folded slot antenna in which the inherent reactance of the folded slot is compensated within desired limits over a frequency band by means of slot feeder reactance in series therewith, the combination of a conductive sheet having a slot therein, a

5 centre conductor located in the slot, feeder connection means for connecting a source of radio frequency energy across the centre conductor and the adjacent edge of the slot, the feeder connection means being located nearer to one end portion of the slot than the other, the slot and the centre conductor thereby defining two electrically asymmetric slot feeders in parallel connected to the feeder connection means whereby the two slot feeders reach at separate frequencies within the frequency band the high value of reactance which prevents the effective feed of energy to the slot from the feeder connection means via the slot feeder.

10 30. A reactance compensated folded slot antenna in which the inherent reactance of the folded slot is compensated within desired limits over a frequency band by means of slot feeder reactance in series therewith, the folded slot including a conductive sheet having a slot therein, a centre conductor located in the slot, feeder connection means for connecting a feeder across the centre conductor and the adjacent edge of the slot, the feeder connection means being located nearer to one end portion of the slot than the other, the slot and the centre conductor thereby defining two electrically asymmetric slot feeders for feeding in parallel from the feeder connection means, and dielectric filling means for filling at least part of the aperture between the slot and the centre conductor, whereby the two slot feeders extending each side of the feeder connection means follow different frequency characteristics for the slot feeder reactances to reach at separate frequencies within the frequency band the high value of reactance which prevents the effective feed of energy to the slot from the feeder connection means via the slot feeder.

15 31. A reactance compensated folded slot antenna in which the inherent reactance of the folded slot is compensated within desired limits over a frequency band by means of slot feeder reactance in series therewith, the folded slot including a conductive sheet having a slot therein, a centre conductor located in the slot, feeder connection means for connecting a feeder across the centre conductor and the adjacent edge of the slot, the feeder connection means being located nearer to one end portion of the slot than the other, the slot and the centre conductor thereby defining two electrically asymmetric slot feeders for feeding in parallel from the feeder connection means, whereby the two slot feeders extending each side of the feeder connection means follow different frequency characteristics for the slot feeder reactance to reach at separate frequencies within the frequency band the high 20 value of reactance which prevents the effective feed of energy to the slot from the feeder connection means via the slot feeder.

25 32. A reactance compensated folded slot antenna as claimed in claim 30, wherein the centre conductor comprises two parts, one extending along the slot in one direction from the feeder connection means and one extending along the slot in the opposite direction, one part being smaller transversely than the other and the dielectric filling means being located in the aperture of the slot containing the one part of the centre conductor.

30 33. A reactance compensated folded slot antenna as claimed in claim 1 wherein the centre conductor comprises two parts, one extending along the slot in one direction from the feeder connection means and one extending along the slot in the opposite direction, one part being smaller transversely than the other and the slot likewise comprises two parts, one extending in one direction from the feeder connection means and one extending in the opposite direction, the part of the slot containing the smaller part of the centre conductor being smaller transversely than the part of the slot containing the other part of the centre conductor.

35 34. A reactance compensated folded slot antenna as claimed in claim 31 wherein the centre conductor comprises two parts, one extending along the slot in one direc-

tion from the feeder connection means and one extending along the slot in the opposite direction; one part being smaller transversely than the other.

35. A reactance compensated folded slot antenna as claimed in claim 34 wherein an open box of conductive material is positioned against the conductive sheet so as to enclose within its open edges that part of the sheet in which the slot is located, so forming a resonant cavity for the antenna.

36. A reactance compensated folded slot antenna as claimed in claim 29 wherein an open box of conductive material is positioned against the conductive sheet so as to enclose within its open edges that part of the sheet in which the slot is located, so forming a resonant cavity for the antenna.

37. A reactance compensated folded slot antenna as claimed in claim 30 wherein an open box of conductive material is positioned against the conductive sheet so as to enclose within its open edges that part of the sheet in which the slot is located, so forming a resonant cavity for the antenna.

38. A reactance compensated folded slot antenna as claimed in claim 31 wherein an open box of conductive material is positioned against the conductive sheet so as

to enclose within its open edges that part of the sheet in which the slot is located, so forming a resonant cavity for the antenna.
